UNITED STATES PATENT OFFICE

JAMES F. WHITE, OF RICHMOND, CALIFORNIA, ASSIGNOR OF TEN PER CENT TO EARL W. TERRY, OF RICHMOND, CALIFORNIA, TEN ONE-HUNDREDTHS TO E. W. TERRY, OF ALBANY, CALIFORNIA, AND SIXTY ONE-HUNDREDTHS TO FRED CAUDLE, OF RICHMOND, CALIFORNIA

INTERNAL-COMBUSTION ENGINE

Application filed December 3, 1928. Serial No. 323,479.

This invention relates to an improved internal combustion engine, especially designed for use as a motor for automobiles and similar motor vehicles, and it has more particular reference to that species of engine known in the art as a multi-cylinder two stroke cycle engine.

Briefly described, the principal novelty is predicated upon a structure which is characterized by a series of separate and distinct cylinders, and reciprocating pistons, grouped together in a manner to operate in unison.

The cylinders and pistons are associated with coincident simultaneously operable crank shafts and a single compression and combustion chamber, whereby to provide a common explosion and clearance space.

My principal aim is to generally improve upon motor structures of this general classification, in order to promote a decided advantage gained by increased resistant area, without increasing the bore or stroke, while at the same decreasing the total volume capacity.

A further advantage is predicated upon the utilization of supplemental crank shafts geared or operatively connected with a main crank shaft in proper ratio in order to obtain a desired multiplication leverage in the crank shaft, to insure proper transmission of power properly equalized and balanced, and to further insure steady and uniform operation of the motor.

A further object and advantage is based upon the aforesaid multiple phase of piston and cylinder arrangement, for sake of compactness and convenience, and economy in space.

It serves also to insure favorable positions of the pistons with respect to their respective crank shafts to promote more compression and retarded scavenging whereby to permit a correspondingly retarded exhaust.

Other features and advantages of the invention will become more readily apparent

from the following description and drawings.
In the drawings:

Figure 1 is a vertical sectional and elevational view through a motor constructed in accordance with the present invention, showing a pair of diverging cylinders and pistons forming a single group or series.

Fig. 2 is a similar view showing a slightly modified embodiment utilizing a series of three cylinders and pistons in the group instead of two.

The same principle of operation is involved in both embodiments of the invention, and it is understood that the cylinders and pistons may be arranged in series or groups of two or more, for which reason the term "multiple" is utilized to convey the idea of substituting two or more cylinder and piston structures for the customary single cylinder and piston arrangement.

Since the parts are identical in construction, except for the distinction in angularity, the same reference characters will be utilized throughout both views to designate like parts.

Proceeding with this in mind, it will be observed that the reference character 3 designates the motor block which comprises an especially designed casting embodying the multiple cylinder structure.

Journaled for rotation in a crank case is the main or centrally arranged crank shaft 4, on opposite sides of which are supplemental spaced parallel crank shafts 5, and 6 respectively.

The reference character 7 designates the head which includes an intake port 8 and an exhaust port 9, both of which communicate with the space 10. Spring pressed valves, one of which is shown, are of course mounted in the head for cooperation with the two ports 8 and 9. The valves are of course operated in proper timed relation through the medium of a cam shaft 12 located in the overhead casing.

The space 10 operates as a combined compression combustion chamber, thereby providing a common explosive chamber for the multiple piston and cylinder arrangement.

In Fig. 1, I show a pair of cylinders 13 and 14 disposed at proper angles with respect to the chamber 10. Individual pistons 15 and 16 are reciprocable in these cylinders, and are operatively connected by rods 17 with the crank shafts 5 and 6 respectively. 10 These crank shafts, in the present showing, are provided with gears 18 and 19 in mesh with a master gear 20, on the main crank shaft 4.

15 In the arrangement seen in Fig. 2, a third cylinder 21 is provided and the reciprocatory piston 22 therein, is connected by way of the connecting rod 23, with the main crank shaft 4. The lower face of the head 7 in this form of the invention has inclined side portions disposed at right angles to the inclined cylinders and the pistons therein and the intermediate portions of the lower face of the head is horizontally disposed above the vertical cylinder 21 and in this manner the right angularly disposed abutment is provided for each cylinder. Hence, it will be seen that two or more cylinder and piston devices may be provided for each group or series, all of them having open communication with the common compression and explosion chamber 10.

From the foregoing description and drawings, it will be seen that I have conceived, evolved, and produced a new type of multiple cylinder motor characterized by a greater compactness and convenience, in arrangement of parts, distinguished by simplicity and economy, and such in construction as to minimize resistance in power transmissions, 35 to economize in fuel consumption, and to better fulfill the requirements of an engine of this class from a standpoint of efficiency in operation.

It is believed that by considering the description in connection with the drawings, a clear understanding of the construction, operation and arrangement will be had. Therefore, a more lengthy description is regarded unnecessary.

50 Minor changes in shape, size, and re-arrangement of details, coming within the field of invention claimed may be resorted to in actual practice if desired.

Having thus described my invention, what 55 I claim as new is:—

An internal combustion engine of the character described comprising a motor block having a single compression and combustion chamber, said block being further provided 60 with intake and exhaust ports communicating with said chamber, a pair of inclined cylinders communicating at their upper ends with the chamber, a vertically disposed cylinder intermediate the inclined cylinders 65 communicating at its upper end with the

chamber, a crank shaft positioned below each cylinder in longitudinal alignment therewith, a piston mounted for reciprocation in each cylinder, connecting rods coupling said piston to the adjacent crank shaft, intermeshing gears fixed on each shaft for coupling said crank shafts together, a head mounted on the block having portions of its lower face disposed at right angle to each cylinder to provide a right angularly disposed abutment therefor.

In testimony whereof I affix my signature.
